UNITED STATES PATENT OFFICE

2,328,045

FEED-WATER HEATER

Eugene Porter Werthen, East Weymouth, Mass.,
assignor to Buena Vista Iron Company, a corporation of New Jersey

Original application July 25, 1941, Serial No. 404,011. Divided and this application July 27, 1942, Serial No. 452,445

5 Claims. (Cl. 257—2)

This invention relates to a combined low pressure feed-water heater, and more particularly to a combined low pressure feed water heater embodying in one unit a plurality of auxiliary heat exchangers suitable for marine use, the present application being a division of my copending application, Serial No. 404,011, filed July 25, 1941, for a combination low pressure feed heater.

Modern high pressure steam plants with three or more stages of feed heating comprise usually a large number of individual heat exchangers, each having its separate shell, heads, interconnecting piping, by-pass piping and valves. These separate units are always expensive to furnish and maintain, and in marine installations particularly, are excessively wasteful of valuable space and weight. A great deal of heat escapes unused because of the exposure of broad radiating surfaces, thus requiring unnecessarily large expenditures for fuel and additional expense for insulating coverings. Also, it is sometimes a difficult proposition to keep a feed heater properly drained and dry, while completely flooding its drain cooler at the same time, yet both conditions are necessary for the most efficient operation.

One object of my invention, therefore, is a closed type straight-tube heater combining within one shell first stage feed heater, gland leakoff condenser, and feed heater drain cooler.

Another object is a combination low pressure unit which insures flooding the drain cooler while keeping the feed heater dry.

Another object is a cheaper and more compact heat exchange system with much less piping and fewer valves and other parts than conventional systems.

Still another object is a low pressure heat exchange system suitable and adapted for marine use.

Numerous other objects and advantages will be apparent from the following description, wherein reference is made to the accompanying four sheets of drawings illustrating the invention and wherein like numerals of reference indicate like parts.

Figure 1 is a top plan view of my three-section feed heater unit.

Fig. 2 is a front elevation of said unit.

Fig. 3 is a section taken along the line 3—3 of Fig. 4, showing the feed heater drain cooler with the tubes broken away in order to disclose the structure more plainly.

Fig. 4 is a section along the center-line of 4—4

of Fig. 1, with the tubes shown broken away as above.

Fig. 5 is an end view of the inlet-outlet end tube sheet.

Fig. 6 is an end view of the return end tube sheet.

Fig. 7 is a section along the line 7—7 of Fig. 4.

Fig. 8 is a functional diagram of the said three-section unit showing by legends and arrows the course of the condensate therethrough.

Referring now to the drawings, my invention comprises a closed type heat exchanger unit employing banks of straight tubes 1, 2, 3, 4, 5, 6, 7 and 8, and combining within the single shell 9 the feed heater drain cooler 10, the gland leakoff condenser 11 and the first stage feed heater 12.

The shell or casing 9 is constructed of welded steel plate, and preferably is rectangular in cross-section as shown, although it may be made in circular or other form if desired. Tube sheets 13 and 14 are welded to the ends of said shell 9, within which are welded the two horizontal steel division plates 15 and 16 separating the three sections of the unit. Said division plates are welded all around to the sides of the shell 9 and tube sheets 13 and 14 to insure pressure tightness between the gland leakoff condenser 11 which is located in the center and operates at approximately atmospheric pressure, and the first stage feed heater 12 located at the top and the drain cooler 10 located at the bottom, both of which latter sections operate under partial vacuum. Tubes in banks 1, 2, 3, 4, 5, 6, 7 and 8 are expanded into the tube sheets at the inlet ends and are packed with metallic or other suitable packing at the outlet ends to permit free expansion of shell and tubes (Figs. 5 and 6). Staggered vertical baffle plates 17, 18 and 19 are welded as shown in each section.

Inlet-outlet waterhead 20 is provided with condensate inlet 21 and condensate outlet 22 (said inlet 21 and outlet 22 having if desired tapped connections 23 and 24 respectively for the insertion of conventional thermometers 23' and 24'), and internal division walls 25, 26, 27 and 28 forming chambers 29, 30, 31, 32 and 33.

Return waterhead 34 is supplied with recirculating connection 35, tapped holes 36 (closed ordinarily by plugs) for cleaning when necessary, and internal division walls 37, 38 and 39 forming chambers 40, 41, 42 and 43.

Each waterhead is bolted or otherwise firmly secured to its respective tube sheet, and provided with gaskets or the like means well known to the art for pressure tightness.

Feed heater drain cooler 10 is provided with drain inlet port 44 and drain outlet 45 near opposite ends thereof, and connection 46 therebetween. Gland leakoff condenser 11 has vapor inlet port 47, and drain outlet 48 at the opposite end thereof. Adjacent to said drain outlet 48 is gland exhaust port 49, connected by pipe 50 to motor driven exhaust fan 51 mounted on foundation 52. Intermediate between fan foundation 52 and waterhead 13, on the top of the shell 9, is located bleeder steam port 53 to first stage feed heater 12, said bleeder steam port having at the bottom thereof perforated inlet plate 54. Coupling 55 connects to drain line 55' to main condenser (not shown), feed heater temperature is indicated by a thermometer 56' on coupling 56, and pressure is known through a conventional vacuum pressure gage (not shown) on coupling 57. Port 58 is connected by drain regulator 59 and water glass 60 to drain cooler connection 46, and drain port 61 connects by half-pipe 62 fitted with vent 63 to inlet port 44 in drain cooler 10, wherein drain outlet 45 is connected by pipe 64 and throttle valve 65 and further piping to the main condenser.

Under operating conditions, the above-described unit is located in the feed circuit between the air ejector condensers and the second stage deaerating feed heater (not shown). Condensate coming from the air ejector after condensers enters the inlet connection 21 at the bottom of the inlet-outlet waterhead 20 and flows successively through the passes of tube banks 1 of the drain cooler 10, tube banks 2 and 3 of gland leakoff condenser 11, and tube banks 4, 5, 6, 7 and 8 of feed heater 12 to the outlet connection 22 at the top of said waterhead 20.

The feed heater section 12 receives heating steam from the bleeder on the low pressure turbine (not shown) which at full power will maintain a steam pressure in the heater shell of about 8 pounds per square inch absolute. Steam enters near one end of the shell through bleeder steam port 53, and is directed several times across the tubes by internal baffle plates 19. Feed heater drains are conducted by drain outlet port 61 through half-pipe 62 to inlet port 44 opening into drain cooler 10. After traversing the passes of baffle plates 17 in the said drain cooler, the cooled drains are discharged to the main condenser (not shown) through the drain level regulator 59 and throttle valve 65 arranged to keep feed heater free and drain cooler full of drains at all times.

The air and vapor mixture coming from the turbine glands enters one end of gland leakoff condenser 11 through vapor inlet port 47 and is directed a number of times across tubes 2 and 3 by baffle-plates 18 in flowing to the gland exhaust port 49 at the opposite end where the mixture, predominantly air at that point, is withdrawn through pipe 50 and discharged to atmosphere by exhaust fan 51. Drains from said gland leakoff condenser 11 are discharged to the fresh water drain collecting tank (not shown) through drain outlet 48, which is located at the fan suction end so that drains and air vapor mixture flow in the same direction.

At low power, with small quantities of condensate available, provision is made for recirculating part of the condensate to the main or dynamo condensers through connection 35 at the exit to the last pass of the gland leakoff condenser 11 on return waterhead 34. Although the recirculated condensate passes through drain cooler 10 ahead of the gland leakoff condenser 11 there is little or

no heating of the condensate in said drain cooler 10 at low power because under that condition the steam supplied to the first stage heater 12 from the bleeder on the low pressure turbine is at approximately the same temperature and pressure as the exhaust to the main condenser, hence the drains going to the drain cooler 10 are only slightly above the temperature of the condensate leaving the condenser. The condensate entering the said drain cooler 10 may be at the same or even higher temperature than the drains since at that point it has already received some heat from the air ejector condensers.

In port, with the main turbine shut down, the unit is left in the feed circuit. The condensate from the dynamo condenser is then sufficient to condense the steam from the generator turbine glands. The feed heater 12 and drain cooler 10 are then inoperative.

Should it become necessary to shut down the unit for repairs or inspection the condensate may be by-passed through the line 66 to the second stage deaerating heater with some loss in overall efficiency, and the feed heater drained through the drain line 55'. During the shutdown period the vapor from the turbine glands will be discharged to the engine room. If the shut-down is made under port conditions there will be only the negligible amount of vapor from the dynamo turbine glands to be discharged to the engine room and negligible loss in efficiency.

Although I have thus described my invention in considerable detail, I desire it to be clearly understood that I reserve the right to use such substitutions, modifications or equivalents thereof as are embraced within the scope and spirit of my invention as defined in the appended claims.

Having thus described my invention, what I claim as new and useful and desire to secure by Letters Patent is:

1. A combined feed heater unit comprising an inlet port for receiving condensate, a feed heater drain cooler having a tube pass for the passage of said condensate, a gland leakoff condenser having two tube passes for the further passage of said condensate, a first stage feed heater having a plurality of tube passes for the final passage and heating of said condensate, means for connecting in series relation the drain cooler and the gland leakoff condenser and the feed heater, and an outlet port for discharging said condensate.

2. In a multi-stage steam plant including main and dynamo condensers and air ejector after condensers, a closed type heater comprising in one shell a drain cooler, a gland leakoff condenser, a feed heater, a plurality of communicating means for connecting the drain cooler and the gland leakoff condenser and the feed heater in series relation, and a recirculating outlet on one of said communicating means adjacent the discharge end of the gland leakoff condenser, whereby condensate coming from air ejector after condensers passes successively as a coolant through the drain cooler and the gland leakoff condenser and part thereof is then recirculated through the recirculating outlet to the main or dynamo condensers and the remainder is heated and discharged by the feed heater.

3. In a multi-stage steam plant including external condensers and a turbine having glands and bleeder, a combined unit having straight tubes for the passage of condensate and comprising a single enclosing shell, a feed heater section therein, a perforated inlet connection in

the top of said feed heater section for admitting bleeder steam, staggered internal vertical baffles for directing the steam across the tubes therein to heat the condensate, a gland leakoff condenser beneath the feed heater for separating air and vapor coming from the turbine glands, a drain cooler section beneath the gland condenser, means for conducting drains from steam condensing on the tubes from the feed heater to the drain cooler section, and means for controlling the discharge of drains from the drain cooler in response to the level of the drains in the conducting means.

4. In an apparatus of the class described, a unitary shell having two partition walls, one above the other, extending substantially horizontally across said unitary shell so as to divide the interior of the unitary shell into three sections, comprising from top to bottom a feed heater, a turbine gland leakoff condenser, and a feed heater drain cooler, the said sections being respectively separated by the said horizontal walls, tubes in each section for the passage of condensate from a condenser, means for connecting said sections in series, means for circulating steam about the tubes for heating the condensate in the feed heater, means for separating air and vapor coming from turbine glands in the gland leakoff condenser and separately expelling said air and vapor, means for conducting drains from the feed heater to the drain cooler, means for maintaining the level of said drains midway between the feed heater and the drain cooler and means for discharging the spent drains.

5. In a multi-stage steam plant including main and auxiliary condensers, air ejector inter and after condensers, second stage deaerating feed heaters, turbine glands and bleeder, and fresh water drain collecting tank, a low pressure feed heater unit comprising a unitary containing shell substantially rectangular in transverse section, a plurality of horizontal division plates forming in order from the bottom rectangular superposed compartments in said shell comprising a drain cooler, a gland leakoff condenser,

and a first stage feed heater, vertical baffle-plates in each compartment forming passages therein, a tube-sheet secured at each open end of said shell, a plurality of straight horizontal tubes extending between said sheets and opening on the outside of said sheets for heat-transference and passage of condensate, a water head at each end of the sheets, an inlet port in one water head at the bottom thereof for receiving condensate from the air ejector after condensers, internal division walls in both water heads for directing the flow of condensate in proper sequence through the tubes in the various compartments, a steam port for receiving steam from the turbine bleeder to heat the condensate in the tubes of the first stage feed heater, a perforated inlet plate for preventing direct impingement of high velocity steam on the said tubes of the first stage feed heater, an outlet port at the top of one water head for discharging the heated condensate from the first stage feed heater tubes, an exhaust port at the opposite end of the feed heater from the steam port, an inlet port in the drain cooler, a half-pipe welded to the shell for conducting drains from the exhaust port of the first stage feed heater to the drain cooler for cooling, a drain regulating device for controlling the level of drains to keep the drain cooler flooded therewith and the first stage feed heater dry, means for conducting excess drains from the drain cooler to the main condenser, an inlet connection for receiving the air and vapor mixture from the turbine glands at one end of the gland leakoff condenser, an outlet connection at the opposite end of the gland leakoff condenser, an exhaust fan mounted on said unit and connected to said outlet connection for drawing by suction the said air and vapor mixture through the passages of the baffle-plates in the gland leakoff condenser and discharging same to atmosphere, and a drain outlet located at the fan suction end of the gland leakoff condenser for discharging drains therefrom to the fresh water drain collecting tank.

EUGENE PORTER WORTHEN.
